Primary Examiner — Robin V Webster

Assistant Examiner — Keith J Wilson

(74) Attorney, Agent, or Firm — Morgan, Lewis &
Bockius LLP

See application file for complete search history.

(57) **CLAIM**(56) **References Cited**The ornamental design for a tent frame with eaves, as shown
and described.

DESCRIPTION

U.S. PATENT DOCUMENTS

1,061,547 A	5/1913	Kennedy
1,347,107 A	7/1920	McCann
3,888,056 A	6/1975	Kelly
4,286,612 A *	9/1981	Neal
		A01K 1/033
		135/115
4,630,627 A	12/1986	Windows
4,641,676 A *	2/1987	Lynch
		E04H 15/50
		135/115
4,793,371 A *	12/1988	O'Ferrell
		E04H 15/44
		135/118
4,944,321 A *	7/1990	Moyet-Ortiz
5,224,507 A *	7/1993	Vosse
		E04H 15/58
		135/115
5,275,188 A	1/1994	Tsai

FIG. 1 is a perspective view of our new design of a tent
frame with eaves;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The broken lines in the above described FIGS. 1-7 are for
illustrative purposes only, depict environmental matter only,
and form no part of the claimed design.**1 Claim, 7 Drawing Sheets**# US D859,564 S
